UNITED STATES PATENT OFFICE

WILLIAM GLUCKMAN, OF NEW YORK, N. Y.

FILM CABINET

Application filed October 19, 1929. Serial No. 400,793.

The object of my invention is to provide a cabinet of this kind which will hold fifteen films with safety in a smaller space than has heretofore been possible. This is desirable because the space in fire-proof projecting booths which is available is exceedingly limited, and yet the films must be accessible and easily and quickly inserted or withdrawn. Furthermore, provision must be made so that should spontaneous combustion occur in a film, no further damage will be done and no other film will be ignited, so that the cabinet is safe as well as compact. A further object is to make a cabinet which may be made in sections, one section to be put on top of another, until the desired capacity is obtained. These and other objects are accomplished by my invention, one embodiment of which is hereinafter more particularly set forth.

For a more detailed description of my invention, reference is to be had to the accompanying drawings, forming a part hereof, in which

25 Figure 1 is a front elevation of my improved cabinet, three sections and a top being shown;

Figure 2 is a side elevation of the same;

30 Figure 3 is a sectional view taken on the line 3—3 of Figure 1, looking in the direction of the arrows;

Figure 4 is a sectional view taken on the line 4—4 of Figure 3, looking in the direction of the arrows;

35 Figure 5 is an enlarged longitudinal section through a compartment having a film;

Figure 6 is a sectional view taken on the line 6—6 of Figure 5, looking in the direction of the arrows;

40 Figure 7 shows certain parts detached so as to reveal details of construction.

Throughout the various views of the drawings, similar reference characters designate similar parts.

45 In Figures 1 and 2 are shown sections 1, 2 and 3, and a top 4. As the sections 1, 2 and 3 are identical, a description of one will answer for all. Each section has an exterior wall 5 which extends on three sides and has an external sheet 6 and an internal sheet 7,

united at the front by a suitable joint 8 which may be of any suitable form but which are preferably made as shown in Figure 3, with interlocking seams. There is no top or bottom to these walls 5 as one section stands on the other except that the lowest section has an extra bottom which is fireproof, under normal conditions, and the top section is covered by the top 4. It is important that the air space in the partition 5 between the sheets 6 and 7 should extend from top to bottom for a purpose that will appear below. Each section has at its front a number of door frames 9 which are rectangular in outline and extend from top to bottom, and each door frame is adapted to be closed by a hinged door 10, which is slidably mounted on a pivot 11, which may be circular in cross section at its top and bottom, and square in its cross section throughout the remainder of its length. Each door is also provided with a handle 12. Each door is composed of two sheets, 13 and 14, secured together in any suitable manner and preferably in the way indicated, and the sheet 14 is bent so that the top is tapered where it fits against its frame 9, as indicated in Figure 3. There is also in the door frame a projection 15 which is in front of the door and the door is lifted over the same when opened or closed, this being permitted because the door slides on the pivot 11 and the frame 9 is a little higher than the door, although only slightly so. However, the difference is sufficient to enable the projection 15 to be cleared. This simple construction does away with the need of all latches and catches, and well holds the door closed with a tight joint which is very important as will appear below.

46 Each door 10 is opposite a cell 16 extending from front to rear, and reaching the rear wall 5 of each section. Each cell 16 is composed of an inner casing 17 of asbestos so that each cell is completely lined with asbestos on all sides except the front, and the door 10 may be lined with asbestos, if desired. Exterior to this asbestos casing 17 is a sheet 18 of metal which securely reinforces and holds the asbestos. The top sheet 18 is flanged upwardly at 19 to fit snug

against the inner sheet 7 of the wall 5 and it is preferably held in position by means of a cap 20, which extends over this sheet 7 as well as over the flange 19. At the rear of each cell 16 and near the door of the same, there is an opening 21 which runs to a space between the rear wall of the cell and the partition 7 and at the top of partition 7 is another opening 22 which runs into a space surrounded by a bent plate 23 which is secured to the exterior of this partition and between it and the plate 8, and this partition is preferably riveted in place so as to be secured at all times. The purpose of this is to let the products of combustion, should a film in the cell get on fire, rush out through the openings 21 and 22 and through the hollow of the plate 23 and thereby escape between the partitions 7 and 8 to the top 40 from where these products may be drained through an opening 24 at the top of the cover 4 and be taken from the booth and building so that no poisonous fumes will be confined in a small space occupied by human beings, as such fumes are very dangerous. The long and tortuous passage for these fumes, which is constantly upward, will prevent any ingress of flames to a cell where there is no combustion, so that the film in one cell may 50 get on fire without in any way endangering or disturbing the films in other cells. It will be noted that the cells are each separated by large air spaces 25.

At the bottom of each cell 16 is a floor 26 which is secured to the side and rear walls of the cell in any suitable manner and also to the front, as by riveting, and at the front this floor is provided with two parallel slots 27 (see Figure 7) which cause a tongue to be formed between them and on this tongue and in these slots is placed a loop 28 which is pivotally connected to an ejector 29 in any suitable manner so that the front of this ejector is pivoted and the rear of it may rise or fall according to the opening of the door as will now appear. This ejector is well weighted at 30 at its rear end so that it will fall by gravity or else be lifted by mechanism now to be described. The under surface of this ejector rests against a bent lever 31 pivoted at 32, just below the lower surface of the floor 26 and to this floor, as shown in Figure 5, and the lower end of this bent lever 31 is pivotally connected to a link 33 that runs to a crank 34 which is fixed to the pivot 11 so that when the door 10 is opened, the link 33 is drawn to the front, as shown in Figure 6, and the ejector 29 is raised as shown in dotted lines in Figure 5, and when the door is closed, this ejector is lowered so that the film roll 35 rests in place with no inclination to roll against the door 10. When the door is opened, the ejector is raised at its rear and the film rolls out. When the film is inserted, it rolls from the hand of the

operator on to the ejector and before it has time to reverse its movement, the door is closed and there is no tendency of the roll to come against the door.

In view of the foregoing, the operation of my invention will be readily understood. Under normal conditions, the films are stored as above described, and if one of them gets into a state of combustion from internal or other causes, it has to burn in an atmosphere where there is very little air, and the products of combustion will go out through the vents above described, and there is no chance of one film setting another on fire. This is most important, as it is difficult to make a practical cabinet which can withstand the effects of all films being in a state of combustion at once. Under normal circumstances, there is no combustion, and each film is inserted and removed with facility as above described, and very little space is required for the functioning of the doors 10, as they are pivoted on the long and not the short side. Furthermore, as many sections may be used as required, and each section is interchangeable with the other, so that any may be replaced or put above or below another, as desired. It will be noted that the sheets 7 and 8 are slightly offset at their upper edges so as to permit one section to be fitted on another, as above set forth.

While I have shown and described one embodiment of my invention, it is obvious that it is not restricted thereto, but that it is broad enough to cover all structures that come within the scope of the annexed claims.

Having thus described my invention, what I claim is:

1. A cabinet section having a number of cells in which films may be stored, constantly open means for removing the products of combustion from each cell, a vertical door hinged on its vertical side for closing each cell and means connected with each door for ejecting a film from its cell so that it may roll into the hands of a person opening the door.

2. A cabinet for storing films comprising a plurality of sections, each of which is provided with a plurality of vertical, rectangular cells with air spaces between them, an asbestos lining for each cell, a constantly open flue back of each cell for permitting the escape of products of combustion in that cell, means connected with each door for ejecting a film from its cell so that it may roll into the hands of a person opening the door, and a vertical rectangular hinged door for closing each cell, the hinge being on the vertical longer side of the door.

3. A section of a cabinet which is composed of two sheets separated from each other and means for holding them in fixed relation for forming the walls of three sides of this cabinet, with a constantly open flue between

them, door frames at the front of this section, a series of cells connecting the door frames with the rear wall, a door for each cell, each door being slidably mounted on a pivot and a lug in a door frame over which the door may pass so that it will stay in place when closed.

4. A section of a cabinet for films, which is composed of two bent sheets separated from each other, and means for holding them in fixed relation for forming the walls of three sides of the cabinet with a flue between them, openings from each cell to this space, door frames at the front of this section and secured to said sheets, a cell connected to each door frame and a hinged door for closing each cell.

In testimony whereof, I have hereunto set my hand this 16th day of October, 1929.

20 WILLIAM GLUCKMAN.
